ATTORNEY

UNITED STATES PATENT OFFICE.

JONAS W. SELANDER, OF GALESBURG, ILLINOIS.

APRON.

Application filed September 13, 1922. Serial No. 588,012.

To all whom it may concern:

Be it known that I, JONAS W. SELANDER, a citizen of the United States, residing at Galesburg, in the county of Knox and State of Illinois, have invented new and useful Improvements in Aprons, of which the following is a specification.

The object of this invention is to provide an apron especially intended for the use of 10 women when working around motor cars, or doing other moderately heavy work.

A further object is to provide a garment which may be quickly placed in position, which will effectively protect the clothing of 15 the wearer, and which may be advantageously used by any one doing rough work.

A still further object is to provide a garment which will serve the purpose of an apron of the usual type, but which also 20 resembles the knickerbocker trouser.

In the accompanying drawings,

Figure 1 is a perspective view of the apron, from the rear side;

Figure 2 is a horizontal section through 25 the several thicknesses at hem 18;

Figure 3 is a horizontal section through the bottom portion of one of the legs.

A strip of heavy cloth is originally approximately rectangular in shape, and the 30 lower portion is divided at 10 to form leg members 11 and 12, in the lower hem 13 of which is sewed, in each case, a split resilient ring 14, which will permit of holding the lower end of the leg of the garment in position, near the ankle. The edge portions of 35 the legs are not otherwise connected.

The middle portion of the garment is designated 15, and stretching horizontally across this portion and extending downwardly is an extra thickness of material 16 40 overlapping the inner edges of the members 11 and 12, in the manner shown.

Within the hem 18 forming the waist-

band is a curved and resilient metallic element 19, of approximately ring form, and 45 adapted to hold the garment around the waist of the user, without other securing means.

The upper portion of the front of the apron, or the bib, is designated 20, and has 50 connected therewith a strap 21, designed to pass over the shoulders and around the neck, this strap being provided with a buckle 22. After the correct length for the strap has been determined, this element may be passed 55 over the head, so that it will not be necessary to manipulate any securing device whatever in placing the garment in position and removing it, except to temporarily open the split rings. The upper and lower rings 60 tend to draw the long edge portions 24 and 25 together, so that the appearance is much the same as in the case of the knickerbocker garment.

What I claim is—

A garment formed of a strip of material having approximately straight sides, the strip having its lower portion divided to form legs and the upper portion being formed into a waist band, a bib connected 70 with the waist band, a curved resilient device connected with the waist band, curved resilient devices connected with the legs and adapted to retain these portions of the garment in position, and an inner layer of material overlapping the inner edges of the leg portions, the upper edge of said inner layer terminating approximately at the point where the strip is divided to form the legs, and the lower edge of the strip tending to 80 move inwardly between the legs of the wearer, under the action of the resilient devices connected with the legs.

In testimony whereof I affix my signature.

JONAS W. SELANDER.
